UNITED STATES PATENT OFFICE.

PAUL L. CLARK, OF CHICAGO, ILLINOIS, ASSIGNOR TO GENERAL ELECTRIC COMPANY, A CORPORATION OF NEW YORK.

SYNCHRONISM-INDICATOR.

SPECIFICATION forming part of Letters Patent No. 789,488, dated May 9, 1905.

Application filed October 19, 1903. Serial No. 177,586.

To all whom it may concern:

Be it known that I, PAUL L. CLARK, a citizen of the United States, residing at Chicago, in the county of Cook, State of Illinois, have 5 invented certain new and useful Improvements in Synchronism-Indicators, of which the following is a specification.

This invention relates to devices for indicating the proper instant for closing the line-switch of an alternating-current generator, synchronous motor, or rotary converter, which is to be connected in parallel with another similar machine already in operation. It is well understood that this must be done when 15 the machines are in step; but under ordinary conditions it is uncertain when that instant occurs. The machines are never thrown together when the indicating-lamps are fluctuating with short beats, and as the beats grow 20 longer the interval of darkness or brightness, as the case may be, extends over so long a period that it is difficult to guess just the right instant to close the switch.

My invention aims to eliminate any possible doubt on this score; and it consists in a signaling device, such as an indicating lamp or lamps controlled by a switch, which is kept open so long as the phase displacement is at a maximum and is closed by a solenoid only 25 when the beats become very long and at the middle portion only of each beat.

In the accompanying drawing is a diagram of circuits embodying my invention.

The machine A is connected with the leads 35 1 2 3 and is supposed to be running. The machine B is assumed to be coming up to speed, its leads 1^a 2^a 3^a being open at the switch 4.

At 5 is an indicating lamp or lamps in a connection around the switch 4 and across 40 similar leads 1 1^a, so that when the machines are in step the lamps will be dark.

The lamp-circuit is controlled by a switch 6, which when no current is flowing is held normally closed by a yielding device, such as 45 a spring-arm 7, fixed at one end. Adjusting-screws 8 8' enable the pressure of the switch-contacts to be varied. Connected with the arm 7 is the laminated core 9 of a solenoid 10, which is connected in shunt to the lamps 5

and switch 6, preferably through an adjustable resistance 11. The upper end of the core is suitably guided, preferably by a light spring-arm 7^a, parallel with the arm 7. If desired, a lamp or lamps 12 may be shunted around the lamps 5 and switch 6, though these are not 55 essential.

The operation of my invention is as follows: When the machines are out of step and there is consequently an exchange of potential between them, the lamps 12 flash brightly, 50 and the voltage across the solenoid is sufficient to lift its core against the tension of the springs and open the switch 6, the vibration of the core being so rapid and so small that the switch remains open and no light appears in the lamps 55 5. As the speed and phase of machine B approach the speed and phase of machine A and the voltage across the line-switch drops the vibrating core 9 gradually drops until at some predetermined point when the machines are 60 nearly in step the spring-arm 7 causes the switch 6 to close the circuit of the lamps 5. The closing is only momentary, but is long 65 enough for the lamps to glow dimly, but with a fading light which almost immediately dies 70 out. This is the instant for closing the line-switch, for it is the point of the least difference in phase between the two machines. If the lamps 12 are used, they will act like ordinary series indicating-lamps and by this 75 flashing assist in determining the proper instant to close the line-switch; but instead of having to guess at the middle point of the long period of darkness the operator will be enabled by my device to judge of this point 80 very accurately, for the switch 6 is not closed until said point is nearly reached, and the subsequent and almost immediate darkening of the lamps 5 is a close indication of the crossing 85 of the waves. 90

In accordance with the patent statutes I have described the principle of operation of my invention, together with the apparatus which I now consider to represent the best embodiment thereof; but I desire to have it 95 understood that the apparatus shown is only illustrative and that the invention can be carried out by other means.

What I claim as new, and desire to secure by Letters Patent of the United States, is—

- 5 1. A synchronism-indicator comprising an electric signal responsive to exchange currents between machines to be synchronized, a solenoid in shunt to said signal, a solenoid - core controlling a switch in the signal-circuit, and a yielding support for said core.
- 10 2. A synchronism-indicator comprising an electric signal responsive to exchange currents between machines to be synchronized, a solenoid in shunt to said signal, a solenoid - core controlling a switch in the signal-circuit, and an adjustable spring supporting said core.
- 15 3. A synchronism-indicator comprising an incandescent lamp or lamps responsive to exchange currents between machines to be synchronized, a solenoid in shunt to said lamps, a solenoid-core, a spring supporting said core, and a switch-contact carried by said spring and controlling the circuit of the lamps.
- 20 4. A synchronism-indicator comprising an electric signal responsive to exchange currents between machines to be synchronized, a solenoid in shunt to said signal, a solenoid - core controlling a switch in the signal-circuit, a yielding support for said core, and an adjustable resistance in circuit with the solenoid.
- 25 5. A synchronism-indicator comprising an electric signal responsive to exchange currents

between machines to be synchronized, a solenoid in shunt to said signal, a solenoid - core controlling a switch in the signal-circuit, a yielding support for said core, and one or more electric lamps in shunt to the signal- 35 switch.

6. In a synchronism-indicator, means for energizing a signal only during the interval when the phase displacement is at or near the minimum. 40

7. In a synchronism-indicator, the combination of a signal, and a controlling device responsive to exchange currents between the machines to be synchronized and operative to work said signal only when the phase displacement of the machines is at or near the minimum. 45

8. In a synchronizing device, the combination of a relay-magnet responsive to exchange currents between machines to be synchronized, 50 and a circuit controlled by said relay, said circuit being held open by said magnet except when the exchange current is at or near a minimum.

In witness whereof I have hereunto set my hand this 15th day of October, 1903.

PAUL L. CLARK.
